ROTARY FURNACE

Gerhard Brunkow, Magdeburg-Buckau, Germany,
assignor to firm Fried. Krupp Grusonwerk Aktiengesellschaft, Magdeburg-Buckau, Germany

Application January 27, 1934, Serial No. 708,645
In Germany February 14, 1933

6 Claims. (Cl. 266—18)

The present invention relates to rotary furnaces having a number of muffles for carrying out endothermic processes, etc. In such furnaces it is known to locate, parallel to the axis of rotation, muffles for carrying out endothermic processes of all kinds, particularly for the distillation of metals, as zinc or cadmium, so that the charge in the muffles is, during the rotation of the entire furnace system, constantly heated by being brought into contact with the heated muffle wall. This construction has the disadvantage that the muffles are heated wholly or predominantly only from one end of the furnace, so that at the end of the muffle that is remote from the latter there exist temperatures that are considerably less than at the other end of the muffle, which is within the range of the heating flame. The main object of the invention is to produce as uniform a heating as possible of the muffles practically over their entire length.

According to the invention there is employed for the carrying out of such processes as the above a muffle system in which the several muffles, which may be formed of a generally cylindrical shape or approximately so, are supported by discs arranged at right angles to the muffles and in their turn connected together centrally by means of a shaft, which is advantageously insulated. The entire muffle system or shaft supporting discs and muffles then rotates within a fixed furnace chamber, whilst the heating may be effected by means of several burners which are arranged transversely to the direction of rotation so that the heating may be very well regulated.

By way of illustration, various furnaces in accordance with the invention are represented diagrammatically in the accompanying drawings, wherein—

Figure 1 is a longitudinal section of a furnace having a muffle system.

Figure 2 is a section on the line A—B of Figure 1.

Figure 3 represents in longitudinal section a construction of furnace in which a condenser is rigidly connected with the muffle system and

Figures 4 and 5 are longitudinal sections of other constructions of furnace having condensers.

In all the figures of the drawings 1 represents the supporting shaft, which is formed by way of example as an air-cooled tube, and is mounted in bearings 2 and provided with an external insulating sleeve 3. On the tube 1 there are arranged supporting discs 4 and 5 which are provided with linings 4' and 5' and receive the several muffles 6. For further supporting the muffles, in the con-

structions shown in Figures 1 to 4, there are provided metallic supporting discs 7, to which the muffles, in as far as they are metallic, may be attached possibly by welding. The muffle system is rotated, according to Figures 1 to 4, within a fixed furnace structure 8. According to Figure 5, instead of a metallic supporting ring 7, there is provided a supporting ring 9 built of bricks, so that two separate furnace chambers 10 and 11 are produced for the heating of the muffles. This division of the furnace block has for its object to render accessible to the external air the metal ring 12 necessary for supporting the ring 9, so as to prevent the latter from being over-heated.

Referring more particularly to Figure 2, at 13 there is provided a burner the flame of which, after passing through an ante-chamber 14, enters the furnace chamber 16 at 15. It is advisable to rotate the muffle system in the direction of the arrow x so that the surfaces of the charges in the several muffles are approximately parallel and inclined in the direction indicated at 17. The hot gases in passing through the furnace chamber 16 to the flue opening 18 therefore strike all the muffles preferably at the part at which they are covered by the material contained in them. In order that it may be possible to regulate the quantity of the gases that pass through over the supporting tube or under the supporting tube it is advisable to provide further flue openings 19. The regulation of the gas path may be effected according to circumstances by widening or narrowing the flue opening by means of the normally walled-up openings 20. When, in the case of carrying out the endothermic process it is a question of operations in which the access of air is to be prevented, it may be advisable to close the muffle at both ends by means of removable caps 21, the charging and emptying of the muffles being effected by removing the caps.

When, in the endothermic process, gaseous products of the reaction occur and these are to be condensed immediately as for example in the case of the distillation of zinc, it is advisable to arrange the necessary condenser also in the rotary portion of the furnace. This may be effected, as shown in Figure 3, by connecting the supporting tube 1 rigidly with a condenser 22, the mounting of the system then advantageously being effected in such a manner that the tube itself is supported only at one end and the condenser is supported at the other end at 23. The driving of the entire system is effected by a pinion 24. In the construction shown in Figure 3 the feeding of the charge takes place from a bunker 25

through branches 28 by means of a worm 26 and an annular conduit 27. When the bunker 25 is sufficiently full a good air-tight closure is ensured by the charge itself. In the case of this 5 mode of feeding the caps 29 serve merely for the observation and cleaning of the muffles. Each individual muffle is connected by branches 30 with an annular conduit 31 into which the solid products of the reaction are discharged and in which, 10 if required for the purpose of an air-tight closure, there may be built a shut-off device. The gaseous products pass through a retention ring 32 into branches 33 and thence into the condenser 22. The uncondensed portions of the gas are led away 15 at 34.

In the construction of the muffle furnace according to Figure 4, in which also a large collecting condenser is connected with the supporting tube, the muffles do not extend through the 20 end walls of the rotary portion of the furnace, but are connected in a gas-tight manner with two annular chambers 35 and 36. This construction has the advantage that only one branch is necessary in each case for feeding and delivering the 25 products. Feeding is effected again by means of a worm 26 and through a spiral tube 37, whilst delivery is made through a branch 38 into an external helical pipe 39, in which, if required for the cutting-off of the material, there may be 30 built two closure devices. The gaseous products of the reaction pass into the condenser 22 through the branch 40.

In the case of the construction according to Figure 5 charging is effected intermittently by 35 means of caps 41, whilst delivery is again made into a helical tube 39 through branches 42. For condensing the gaseous products there is provided for each muffle a separate condenser 43, which is connected at 44 with the supporting tube 1 and 40 rotates therewith.

The above-described muffle system is suited particularly for the distillation of metals, for example, of zinc, cadmium or mercury, but other endothermic processes may also be carried out in 45 this form of apparatus. When gaseous materials co-operate in the reaction and must be fed into the muffles they may be introduced in a simple manner by means of the worm 26, which is then provided with a hollow shaft. The muffles 50 may be made of heat-resistant metal sheets or of ceramic materials, particularly silicon carbide or fireclay.

Having now particularly described and ascertained the nature of my said invention and in what manner the same is to be performed, I declare that what I claim is:—

1. In a furnace for carrying out endothermic processes, such as the distillation of zinc, cadmium and mercury; in combination, a furnace chamber comprising walls having opposed circular openings; means for heating said furnace chamber; a rotatable unit within said chamber 10 consisting of a central supporting element extending through said furnace chamber coaxial with said openings, a group of muffles surrounding said supporting element, and disks closing said circular openings, said disks having sealing 15 faces fitting closely against corresponding faces in said circular openings; said central supporting element comprising a cylindrical insulating member in the part exposed to the heat of said furnace chamber, to prevent elongation and 20 warping of said supporting element which would impair the sealing effect of said sealing faces.

2. In a furnace for carrying out endothermic processes, such as the distillation of zinc, cadmium and mercury; in combination, a furnace 25 chamber, a rotatable shaft extending through said chamber, an insulating casing on the portion of said shaft within said chamber, the unit consisting of said shaft and insulating casing being provided with a plurality of disks, a plurality of 30 muffles carried by said disks and grouped around said shaft, the walls of said furnace chamber having circular openings which are tightly closed by said disks, and means for heating said furnace.

3. A furnace as described in claim 1 in combination with one or two annular chambers into which the ends of said muffles open, said chambers serving as common transfer means for material passing through all said muffles.

4. A furnace as described in claim 1, in combination with condenser means rigidly connected to said rotatable unit and conducting means between said muffles and condenser means for the passage of gases to be condensed.

5. A furnace as described in claim 1, in combination with individual condensers communicating respectively with said muffles.

6. A furnace as described in claim 1, wherein at least one intermediate supporting disc is provided to subdivide the furnace chamber.

GERHARD BRUNKOW.
